CLAIM

The ornamental design for a washing container for tray as shown and described.

DESCRIPTION

FIG. 1 is a top perspective view of the washing container for tray according to the invention;

FIG. 2 is a top plan view thereof;

FIG. 3 is a bottom plan view thereof;

FIG. 4 is a first side elevation view thereof;

FIG. 5 is a second side elevation view thereof;

FIG. 6 is a third side elevation view thereof; and,

FIG. 7 is a fourth side elevation view thereof.

The broken lines showing portions of the washing container for tray are included for the purpose of illustrating portions of the article and form no part of the claimed design.

1 Claim, 7 Drawing Sheets
